UNITED STATES PATENT OFFICE.

LEO HOFMEISTER, OF MILWAUKEE, WISCONSIN.

VEHICLE-WHEEL.

1,350,457.

Specification of Letters Patent. Patented Aug. 24, 1920.

Application filed July 18, 1919. Serial No. 311,770.

To all whom it may concern:

Be it known that I, LEO HOFMEISTER, a citizen of the United States, and resident of Milwaukee, in the county of Milwaukee and 5 State of Wisconsin, have invented new and useful Improvements in Vehicle-Wheels, of which the following is a description, reference being had to the accompanying drawings, which are a part of this specification.

10 The present invention relates to certain new and useful improvements in vehicle wheels and more particularly to a traction device employed in connection therewith.

One object of the present invention is to 15 provide a vehicle wheel having peripheral projections pivotally carrying oscillatory foot pieces adapted for contact with the road surfaces whereby the load may be supported from one or more of the foot pieces in contact with the roadway, and whereby the foot pieces may be successively brought into supporting relation.

More specifically stated, my invention provides a wheel having oscillatory foot pieces 20 so arranged upon its periphery as to secure heel and toe effects, both the heel and toe portions being adapted for yielding contact with the surface of the ground whereby when the vehicle is propelled or drawn 25 along the highway, the action of the foot pieces will be similar to that of human feet.

Another object of the present invention is to provide a foot piece forming traction means in which the heel portion will be rigid 30 with the foot piece proper, and the toe portion pivotally carried thereby and normally retain in its proper position for engaging the ground by spring means, whereby the same will be returned to the proper position 35 after engagement with the ground.

A further object of the present invention is to provide resilient means for yieldingly holding the foot pieces in position for proper engagement as the wheel is rotated.

40 A still further object is to provide a vehicle traction wheel which is capable of being used in passing over plowed ground and across miry places without cutting ruts, and ordinarily without penetrating the surface 45 of the ground, although the foot pieces may be readily withdrawn when the ground is sufficiently soft to permit such penetration.

My improved wheel is particularly 50 adapted to be used as a traction wheel for climbing steep grades, maximum friction or

tractive effect being secured, and, owing to the fact that the foot pieces are permitted to oscillate, whereby heel and toe effects are secured, I am enabled to operate the wheel 60 with a minimum number of foot pieces without allowing the load to descend in the spaces between successive foot pieces. I thus avoid the effect of walking on stilts and secure an easy, resilient, rolling motion while 65 maintaining the load substantially at a constant level.

With the above and other objects in view which will appear as the description proceeds, my invention resides in the novel construction, combination and arrangement of parts substantially as hereinafter described and more particularly defined by the appended claims, it being understood that such changes in the precise embodiment of the 75 herein disclosed invention may be made as come within the scope of the claims.

In the accompanying drawing, I have illustrated one complete example of the physical embodiment of my invention, constructed according to the best mode I have so far devised for the practical application 80 of the principles thereof, and in which:

Figure 1 is a side view of my improved wheel, the upper portion being broken away 85 and parts of the lower portion being broken away and in section.

Fig. 2 is a sectional view taken through the foot piece connection on the line 2—2 of Fig. 1.

Fig. 3 is an end view of the foot piece, said view being taken on the line 3—3 of Fig. 1, and

Fig. 4 is a transverse sectional view taken through one of the foot pieces on the line 95 4—4 of Fig. 1.

Referring now more particularly to the accompanying drawing in which like parts are identified by the same reference characters throughout the several views.

The body of the wheel, including the spokes 5, and peripheral rim 6 may be of any ordinary construction adapted in the manufacture of wheels, pulleys, etc. The rim 6, however, is provided with a set of 105 laterally projecting legs 7 having a base portion 8 shaped to conform with the outer peripheral face of the rim 6 to facilitate bolting the legs to the rim or welding them thereto.

110 The legs 7 are each provided with spaced flanges or arms 9 and a centrally disposed

flange 10 connecting the inner end of the same to provide stop means as later described. An oscillatory member 11 is pivoted between the arms 9 by means of a pivot pin 12, said member having its portion inwardly of its pivot provided with a pair of spaced apart projections 13 each carrying an adjustable set screw 14 adapted to abut the stop 10, as later described.

- 10 A portion of member 11, outwardly of its pivot is provided near one end with a hook member 15 adapted to receive the end of a resilient yoke member 16 fixed thereto by a rivet or other fastening 17. The member 16 is shaped as best shown in Fig. 1, that is, is directed inwardly from its end secured to member 11, is then directed laterally for a short distance and then outwardly to a point outwardly of the end secured to member 11 and then bent upon itself, and then inwardly and rearwardly to provide an instep 18, and then outwardly and rearwardly. The constructing of the member 16 in this shape insures the best resilient effect, and the forward end 19 of the foot piece is divided in order that the outer portion of the foot piece will comprise two parallel pieces 20 so that the inner half of the foot piece may have the proper resilient action without striking the outer half, as best shown in Fig. 2.

The foot piece 16 is provided with removable tread pieces 21 and 22, the tread piece 21 being rigid with the piece 16 and connecting the free ends of the arms 20, and the tread piece 22 being fixed in a bracket 23 pivotally carried by the foot piece by means of a pivot pin 24 carried by bearings 25 secured to the forward ends of the arms 20 as best shown in Fig. 1. The tread 22 is normally yieldingly held in a position corresponding with the position of tread piece 21 by means of a retractile spring 26 having one end engaged with an arm 27 of bracket 23, and its other end engaged with a bracket 28 carried by the inner half of the member 16.

The entire foot piece has its forward end normally urged outwardly from the rim 6, its entire limit of movement by means of an extensile spring 29, carried by a spring guide 30 having its outer end in pivotal connection with bracket 28 and its inner end engaged with an aperture 31 in the rim 6, the spring 29 impinging against the rim 6 and a shoulder on the guide 30 near its outer end.

The operation of my wheel is as follows, considering the same as moved from right to left with reference to Fig. 1: As shown in Fig. 1, one foot piece 16 is illustrated as about to engage the roadway, and the other foot piece as being about to disengage the roadway, the action being as follows: The 65 adjustable set screw 14 of the foot piece, to

the right with reference to Fig. 1, engages the stop 10 making the foot piece substantially rigid with respect to the rim and allows the same to move on pivot 24 of the tread piece 22. The foot piece to the left 70 with reference to Fig. 1 is now engaging the ground and as the rocking movement on pivot 24 of the right hand foot piece continues, the weight is evenly shifted to the left foot piece until the entire weight is carried thereby, when the wheel moves on the pivot 12 until the left hand set screw 14 of the left hand foot piece abuts the stop 10, and this foot piece pivots on its pin 24, the action being the same as described in connection with the other foot piece. 75 80

While the wheel has been described as rotated in but one direction, it will be understood that the same is free to rotate in every direction, the operation being practically the same. By providing the two oscillations, viz: one about pivot pin 12 and the other about pivot pin 24, it is possible to take a longer step, and consequently employ a fewer number of foot pieces than would ordinarily be the case, thereby reducing the bearing surface to a minimum. 85 90

What I claim as my invention is:

1. A vehicle wheel having a rim portion and spaced apart foot pieces pivotally secured thereto, each foot piece having a heel portion and a pivoted toe portion whereby each foot piece has two separate rocking movements similar to a human foot. 95

2. A vehicle wheel having a rim portion and spaced apart foot pieces pivotally carried thereby, each foot piece having a heel portion and a pivoted toe portion whereby each foot piece has first an ankle movement similar to a human foot on its pivot and then a ball movement similar to a human foot on the toe portion pivot. 100 105

3. A traction device for vehicle wheels, comprising a pivoted foot piece, a toe portion pivotally carried by the foot piece, and a heel portion resiliently carried by the foot piece. 110

4. A traction device for vehicle wheels, comprising a foot piece pivotally carried by the wheel and capable of a limited movement, a toe portion pivotally carried by the foot piece, and a heel portion resiliently carried by the foot piece. 115

5. A traction device for vehicle wheels, comprising a foot piece in pivotal connection with the wheel, means adjustably limiting the movement of the foot piece on its pivot, and toe and heel portions carried by the foot piece. 120

6. A traction device for vehicle wheels, comprising a foot piece in pivotal connection with the wheel, means adjustably limiting the movement of the foot on its pivot, spring means normally yieldingly urging the foot piece to its limit of movement in one direc- 125 130

tion, and a pivoted toe portion and a heel portion carried by the foot piece.

7. A traction device for vehicle wheels, comprising a foot piece in pivotal connection with the wheel, means adjustably limiting the movement of the foot on its pivot, spring means normally yieldingly urging the foot piece to its limit of movement in one direction, a toe portion pivotally carried by the foot piece, spring means yieldingly holding the toe portion against movement, and a heel portion carried by the foot piece.

8. A vehicle wheel having a rim portion, foot pieces pivotally connected with the rim portion, spring controlled toe and heel portions carried by the foot pieces and adapted for independent yielding movement, and means yieldingly holding the foot pieces against movement including an extensible spring carried by each foot piece and impinging against the rim portion.

9. A vehicle wheel having a rim portion provided with projections, foot pieces pivotally connected with said projections and provided with resiliently yielding bearing members having heel and toe portions adapted for independent yielding movement, each foot piece including a connecting member, a resilient forwardly projecting arm and an integral rearwardly projecting arm parallel therewith and spaced therefrom, the movement of the connecting member being limited by a stop in one direction and by a

tension spring and a stop in the other direction.

10. A vehicle wheel having a rim portion provided with projections, foot pieces pivotally connected with said projections and provided with resiliently yielding bearing members having heel and toe portions adapted for independent yielding movement, each foot piece including a connecting member, a resilient forwardly projecting arm and an integral rearwardly projecting arm parallel therewith and spaced therefrom, the bearing members being adapted to yield resiliently in the direction of the supporting connecting members, such movement being limited by the connecting member arranged to serve as a stop.

11. A traction foot piece for vehicle wheels comprising a supporting bracket, a resilient yoke member in pivotal connection with the bracket, a toe portion pivotally carried by the yoke member, and a heel portion fixed to the yoke member.

12. A traction foot piece for vehicle wheels, comprising a supporting bracket, a resilient yoke member having one end free, means pivotally connecting the other end of the yoke member with the supporting bracket, a heel portion fixed to the free end of the yoke member, and a toe portion pivoted to the yoke member adjacent its bend.

In testimony whereof I affix my signature. 65
LEO HOFMEISTER.
